DAVID GEORGE GARBARINO AND CHARLES WILLIAM ROESSLE, OF NEW YORK, N. Y.

RETHREADING-TOOL.

1,017,403.

Specification of Letters Patent. Patented Feb. 13, 1912.

Application filed December 28, 1910. Serial No. 599,664.

To all whom it may concern:

Be it known that we, DAVID G. GARBARINO and CHARLES W. ROESSLE, citizens of the United States, and residents of the city of 5 New York, borough of Brooklyn, in the county of Kings and State of New York, have invented a new and Improved Retreading-Tool, of which the following is a full, clear, and exact description.

10 The object of our invention is to devise a tool which will re-form the threads on screws or bolts, and it comprises means for engaging the screw or bolt to be re-threaded, in combination with means having a cutting 15 edge which fits the groove between the threads.

It is designed mainly for use in re-forming V-shaped threads, and it is so constructed that the tool can be adjusted to 20 the size of the bolt which is to be repaired. Our invention can also be used to repair metric threads, or any other thread of triangular shape.

Reference is to be had to the accompanying 25 drawings forming a part of this specification, in which similar characters of reference indicate corresponding parts in all the views.

Figure 1 is a front elevation of our re- 30 threading tool; Fig. 2 is a longitudinal sectional view taken on the line 2—2 of Fig. 1; Fig. 3 is a face view of a modification shown on a smaller scale; and Fig. 4 is a transverse sectional view taken on the line 4—4 of 35 Fig. 3.

The numeral 1 indicates an open frame of suitable shape, which may be rectangular, as shown. This frame has a fixed handle 2 extending from one end, and a boss 3 ex- 40 tending from the opposite end, said boss having a screw-threaded bore to receive another handle 4, the inner end of which is screw-threaded, as shown, and the outer end of which is provided with a milled surface 45 5, which permits the handle to be screwed in or out of the bore 3. The bore of the boss 3 receives a shank 7, which has a smooth surface and is attached to the handle 4 by means of a stud 6 extending from the inner 50 end of the handle 4 and entering a recess in the end of the shank 7. This stud holds the shank 7 in axial alinement with the handle 4 and co-operates with means for preventing the shank 7 from turning or twisting 55 around its longitudinal axis. These means comprise a longitudinal key-way 8 in

the shank 7, which is engaged by a pin 9 carried by the frame 1. The groove 8 is of such a size as to cause the pin 9 to fit loosely therein in order to allow a certain 60 amount of play to the shank 7 in the boss 3, so that when the disk-shaped member 10, carried by the shank, engages the thread of the bolt or screw to be repaired, the shank 7 and the disk 10 will be allowed to turn to 65 the necessary angle to produce the proper fit of the disk 10 into the grooves between the threads on the bolt. This disk 10, as shown particularly in Fig. 2, is mounted on a spindle 11, and is rotatably supported in 70 a yoke on the inner end of the spindle 7, and fits snugly between the arms of the said yoke. The frame 1 also carries on the inside thereof a cross-member 12, which is adjustably mounted in the frame 1 on a U- 75 shaped pin 13, passing through longitudinal perforations 14 in the member 12. The sides of the frame member 1 contain a number of perforations 15, which are separated from one another by distances equal to the 80 distance between the members of the U-shaped pin 13, so that the transverse member 12 can be adjusted in the frame 1 toward and from the boss 3, and held in any desired position by the pin 13 being passed 85 through the holes 14 and 15 in the transverse member 12 and the frame member 1, respectively. The pin, of course, has a snug fit in the holes 14 and 15.

The transverse member 12 carries two 90 spindles 16 mounted in the side thereof facing the member 10. These spindles 16 each carry a suitable number of disk-shaped members 17, which are received by recesses in the transverse member 12, as shown on 95 Fig. 2. As shown, the disk-shaped member 10 and the disk-shaped members 17 are provided with V-shaped edges so that they will fit in the grooves between the V-shaped threads which are to be renewed, and the 100 disks 17 are so mounted on their spindles 16 that a small amount of end play is allowed to these disks, thus allowing the disks to fit a bolt of any size having a thread of almost any pitch. The disks 17 also wobble 105 slightly to fit the slope of the threads.

The modification shown on Figs. 3 and 4 is similar to that shown on Figs. 1 and 2, except that the transverse member 12 and the means for adjusting the same are dispensed with. In this modification there are 110 two spindles 18, which are mounted in the

end of the frame 1, from which projects the fixed handle 2. The spindles are supported by a transverse projection 20 in the end of the frame 1, and the spindles carry on each end thereof disk-shaped members 19, shown as provided with sharp V-shaped edges, as in the case of the disk-shaped members 17. The disks 19 also have end play and wobbling movement like the disks 17.

19 When using the form shown on Figs. 1 and 2, the bolt is put in place so as to be engaged by the disk 10 and the disk-shaped members 17, being held substantially perpendicular to the plane of the frame 1. The 25 transverse member is adjusted toward or from the member 10 to make the re-threading tool fit substantially the size of the bolt which is to be threaded. The final adjustment is then effected by screwing in the 20 handle 4, which pushes the shank 7 and forces the disk 10 in place.

With the form shown on Figs. 3 and 4, all of the adjustment is effected by means of the adjustable handle 4. The bolt or 25 screw to be threaded is simply put in place, with the members 19 engaging its surface, and the handle 4 is then turned until the shank 7 is pushed up far enough to engage the surface of the bolt on the side opposite 30 the members 19, all of the disk-shaped members, when the bolt is in place and the final adjustment effected, engaging the V-shaped grooves between the threads thereof and securing the bolt firmly in position.

35 Whichever form is used, when the parts are adjusted to secure the bolt in place, the disk 10 fits into the groove on one side, and the other disks fit into the grooves of the threads on the other side of the bolt, and 40 when the bolt is turned, or the frame is turned instead, the sharp V-shaped edges of all the disks cut through the grooves, widening them to their original size and thus re-forming threads which have been crushed or 45 bent out of shape.

All of the disks shown on either of the two modifications described may be provided with sharp V-shaped edges and may serve not only to secure the bolt in place, but each 50 may also serve as a cutter to force open and re-shape the threads of the bolt or screw which is being worked; or, if desired, only part of these disks may be used as cutters, the remaining disks serving merely as braces 55 to hold the bolt in place. All of the disks either may be made movable so as to rotate around their supporting spindles, or all may be stationary, or part of them may be stationary and the remaining disks may be 60 movable, so long as they can be adjusted to the slope and pitch of the threads.

It is only necessary in the successful operation of our re-threading tool that one of the disks shown and described be provided with 35 a sharp edge to serve as a cutter for re-

threading, and the remaining disks do not need to serve any other purpose than that of bracing the bolt against the action of the cutting member. The cutting member in such a case may be stationary or may be 70 made rotatable, and in either case it should have a certain amount of play so that it can adjust itself to the slope of the thread to be re-formed, after the manner of the disk 10.

It will be seen from the above that we have 75 devised a practical instrument which is of great utility and which can be employed on any size of bolt having V-shaped threads, to re-form or renew such threads, thus making it possible to effect repairs on an automobile 80 or in a machine shop, or wherever else they are needed, in the shortest possible space of time, and effecting a considerable saving in material, for by means of our re-threading tool old bolts and screws which might otherwise have to be thrown away can be readily repaired for further use.

While our invention is designed to re-thread bolts and screws, it is obvious we may also use it to cut pipes, tubes and the 90 like. In such a case we simply employ the disk 10 as a cutter and replace the other disks with rollers of any suitable shape.

Obviously, we may make such changes in the shape and size of the parts constituting 95 our re-threading tool, as clearly come within the scope and spirit of our invention.

Having thus described our invention, we claim as new and desire to secure by Letters Patent:

1. A re-threading tool comprising an open frame, a plurality of disk-shaped members mounted in said frame and adapted to engage a bolt or screw to be re-threaded at a plurality of points to secure the bolt or screw in position, all of said disk-shaped members being rotatable and one being provided with a cutting edge to re-form the threads of the screw or bolt, and being loosely mounted; the others having end play and wobbling movement.

2. A re-threading tool comprising an open frame, a transversely-mounted adjustable member in said frame, a boss carried by the outside of said frame and having a bore therethrough extending in the direction of the longitudinal axis of the frame, a shank carrying a disk-shaped member on its inner end, mounted in said bore, and disk-shaped members carried by the transverse member in the side adjacent to the disk-shaped member in the end of the shank, said disk-shaped members forming means for securing a bolt or screw in the frame to be re-threaded, one or more of said disk-shaped members being provided with a cutting edge to engage and re-form the threads of said bolt or screw.

3. A re-threading tool comprising an open frame, a transversely-mounted adjust-

- able member in said frame, a boss carried by the outside of said frame and having a bore therethrough extending in the direction of the longitudinal axis of the frame, a shank 5 carrying a disk-shaped member in its inner end, adjustably mounted in said bore, and disk-shaped members carried by the transverse member in the side adjacent to the disk-shaped member in the end of the shank, 10 said disk-shaped members forming means for securing a bolt or screw in the frame to be re-threaded, one or more of said disk-shaped members being provided with a cutting edge to engage and re-form the threads 15 of said bolt or screw.
4. A re-threading tool comprising a frame, a handle extending from one end of said frame, a transverse member adjustably mounted in said frame, a boss extending 20 from the side of the frame opposite the said handle member, another handle member adjustably mounted in said boss, a shank mounted in said boss, terminating within the frame, said shank being connected to 25 the handle member and having a longitudinal key-way in its surface, a pin in the frame, loosely fitting said key-way, a disk-shaped member in the inner end of said shank, and disk-shaped members carried by 30 the transverse member on the side facing the shank, the said disk-shaped members forming means for securing a bolt or screw in position in the frame, the shank disk of said disk-shaped members forming a cutter 35 to fit the threads of the bolt or screw and re-form them, the other disks having end play and wobbling movement.
5. A re-threading tool comprising an open frame, and a plurality of members 40 mounted in said frame and adapted to engage a bolt or screw to be re-threaded at a plurality of points to secure the bolt or screw in position, one of said members be-
- ing provided with a cutting edge to re-form the threads of the screw or bolt, and being 45 loosely mounted to fit the slope of the thread of the screw or bolt, the other members engaging the outer periphery of the screw or bolt to hold the same in position to allow the cutter member to move between the said 50 threads.
6. A re-threading tool comprising an open frame, and a plurality of members mounted in said frame and adapted to engage a bolt or screw to be re-threaded at a 55 plurality of points to secure the bolt or screw in position, one of said members being provided with a cutting edge to re-form the threads of the screw or bolt, and the other members having end play and wab- 60 bling movement to adjust themselves to the pitch of the threads and the slope of the same and hold the bolt or screw in position to allow the cutter member to engage the bolt between the threads. 65
7. A re-threading tool comprising an open frame, and a plurality of members mounted in said frame and adapted to engage a bolt or screw to be re-threaded at a 70 plurality of points to secure the bolt or screw in position, one of said members being provided with a cutting edge to re-form the threads of the screw or bolt, and being loosely mounted to adjust itself to the slope of the threads, the other members being 75 mounted to have end play and wobbling movement to adjust themselves to the slope of the threads and the pitch of the same.

In testimony whereof we have signed our names to this specification in the presence 80 of two subscribing witnesses.
